G. B. Babbitt
ATTORNEY.

UNITED STATES PATENT OFFICE.

CLAUD J. MICK, OF INDIANAPOLIS, INDIANA, ASSIGNOR TO LEADER SPECIALTY CO., INC., OF INDIANAPOLIS, INDIANA, A CORPORATION OF INDIANA.

INTERNAL WRENCH.

Application filed June 14, 1923. Serial No. 645,252.

To all whom it may concern:

Be it known that I, CLAUD J. MICK, a citizen of the United States, residing at Indianapolis, in the county of Marion and State of Indiana, have invented a new and useful Internal Wrench, of which the following is a specification.

It is the object of my invention to provide an adjustable internal wrench, which will grip the inner surfaces of articles of various sizes, and especially pipes and pipe fittings and other round articles, and provides large gripping surfaces so that it will not strain the pipe or other article at the points of contact. Such a wrench is very desirable for use in connection with a fitting whose exterior surface is such that it may not be conveniently gripped or may be injured by the ordinary type of pipe wrench. Such fittings as short nipples whose exterior surfaces are substantially entirely covered by screw threads, and exteriorly threaded flanged bushings, are fittings which may be conveniently handled by my internal wrench.

The accompanying drawing illustrates my invention: Fig. 1 is a perspective view showing my internal wrench being used to grip a flanged bushing; and Fig. 2 is a plan on a slightly larger scale than Fig. 1.

My wrench comprises a threaded rod 10, two jaws 12 and 13 mounted thereon, and preferably a cross-rod handle 14 for turning the rod 10. The two jaws are so mounted on the rod 10 that they may be moved relatively to each other longitudinally of the rod by the action of the screw threads when the rod is rotated relatively to one of the jaws. This provides both for adjustment to articles of different size, and for setting the wrench tight on the article. This adjustment may conveniently be accomplished by mounting one jaw, the jaw 13 as shown in the drawing, on the screw threads 11 of the rod 10, and the other jaw 12 on the end of such rod so that it is restrained from any longitudinal movement relatively thereto. With such arrangement, the jaw 12 is preferably pivotally mounted on the rod 10, to permit it to be swung into the same longitudinal plane as the jaw 11. The pivotal mounting of the jaw 12 may be accomplished in any convenient manner. In the form shown in the drawings the rod 10 has at its end a portion 15 which is reduced in diameter to form a shoulder. The jaw 12 is

provided with a countersunk hole of suitable size to fit the portion 15. The jaw 12 is placed in position on the portion 15, and the end of the rod is then enlarged, as by peening, to fill the countersunk portion of the hole and hold the jaw 12 in place against the shoulder on the end of the rod 10 while still permitting it to turn. The exterior faces of the jaws, or those faces which grip the pipe, are preferably corrugated convex cylindrical surfaces, of rather large size, so that they may effectively grip the interior surface of the pipe over considerable areas and thus avoid straining the pipe.

In operation, the rod 10 is turned relatively to the jaw 13 until the two jaws 12 and 13 are close enough together to enter the pipe or fitting it is desired to grip. After the jaws are inserted in the pipe, the rod 10 is rotated by means of the handle 14, and thereby the jaws 12 and 13 are moved apart by the action of the screw threads 11 until a firm grip is secured on the interior surface of the pipe, which may then be turned as desired.

I claim as my invention:—

1. An internal pipe wrench, comprising a screw-threaded rod, a jaw mounted on the screw threads of said rod, and a second jaw pivotally mounted on said rod, the exterior surfaces of said jaws being corrugated to grip internal surfaces.

2. An internal pipe wrench, comprising a screw-threaded rod, two jaws rotatably mounted on said rod and arranged to be moved relatively to each other longitudinally of the rod by the action of the screw threads when the rod is rotated relatively to one of said jaws, the exterior surfaces of said jaws being corrugated to grip internal surfaces.

3. An internal pipe wrench, comprising a screw-threaded rod, two jaws rotatably mounted on said rod and having their outer surfaces as the work-engaging surfaces, said jaws being arranged to be moved relatively to each other longitudinally of the rod by the action of the screw threads when the rod is rotated relatively to one of said jaws.

In witness whereof, I have hereunto set my hand at Indianapolis, Indiana, this 12th day of June, A. D. one thousand nine hundred and twenty-three,

CLAUD J. MICK.
